UNITED STATES PATENT OFFICE.

EDWARD J. PLAYFOOT, OF GALETON, PENNSYLVANIA.

RESILIENT WINDOW STOP.

Application filed November 4, 1924. Serial No. 747,808.

To all whom it may concern:

Be it known that I, EDWARD J. PLAYFOOT, a citizen of the United States, residing at Galeton, in the county of Potter and State 5 of Pennsylvania, have invented certain new and useful Improvements in Resilient Window Stops, of which the following is a specification, reference being had to the accompanying drawings.

10 This invention relates to a window stop for the purpose of holding the sashes braced against the stops of a window and thus causing the sashes to frictionally hold at any point to which they are shifted, and the 15 object of the invention is to provide a device of this character including a spring-supported roller mounted upon one window sash and bearing against the other window sash.

20 A further object in this connection is to provide a very simple, cheap and easily applied device of this character which will not only hold the sashes in their adjusted positions but hold the sashes tight against 25 the stop so as to prevent the entrance of air and prevent the sashes from rattling.

A still further object is to provide in connection with a roller stop of this character means for latching the sash upon which the 30 stop is mounted from upward movement when the sash is lowered.

Other objects will appear in the course of the following description.

My invention is illustrated in the accompanying drawing, wherein:

Figure 1 is a perspective view of a portion of a window and its casing showing the application of my device thereto;

Figure 2 is a sectional view through the 40 window casing showing the bolt holding the casing closed.

Referring to this drawing, A designates the lower sash, B the upper sash, and C the frame of the window. These sashes are constructed as is usual. My roller stop comprises a supporting bracket formed of a relatively heavy resilient wire. This is so formed as to provide a looped portion 10 adapted to rest upon the meeting rail of the lower sash, a portion 11 which extends downward and bears against the outer face of one side sash rail, a portion 12 which extends upward in an inward curve, and a cross bar 13 carried by the portion 12 at its upper end and upon which is mounted a roller 14. I have illustrated the supporting means for

the roller 14 as being composed of two strands of wire, but it will be understood that any other arrangement of this character might be made and achieve the same result, though preferably wire is used as being the cheapest material.

Preferably the face of the window is slightly grooved to receive the two sides of the portion 10, and a cap plate 15 may be disposed over the upper end of this side rail of the window sash and clamped down so as to hold the bracket in place. Preferably, though not necessarily, the side rail is formed with an opening 16 facing the window jamb. Disposed within this opening is the sash bolt 17 which may be projected by a spring into an opening 18 in the window jamb and which is retracted by means of a pin or stud 19 connected to the bolt and extending upward through a slot 20 in the plate 15.

It will be seen that this device when placed upon a lower window sash, as above explained, causes the roller to bear against the upper window sash to a degree which will force this upper window sash against its appropriate stops and prevent any rattling of the upper window sash. The same force which urges the roller up against the upper sash will cause the lower sash to be urged inward or against its stop. Thus the two sashes will be held from rattling and either sash may be raised or shifted and held by the frictional engagement of the 90 roller with the window sash B against any accidental movement when the window sash A is lowered to its full extent. The bolt will project into the keeper formed in the jamb and thus the lower sash will be locked 95 against upward movement until the keeper is withdrawn.

While I have illustrated certain details of construction and arrangement of parts, I do not wish to be limited thereto as it is obvious that these may be changed in minor respects without departing from the spirit of the invention as defined in the appended claims.

I claim:

1. A window stop of the character described comprising a supporting member having a horizontal portion adapted to rest upon the upper face of the lower window sash, a vertical portion to extend down 110 against the face of the lower sash and a portion extending upward from the lower end

of said vertical portion to a point above the horizontal portion and then inward, this last named portion being resilient, and a roller carried upon the upper end of the last 5 named portion and adapted to bear against the upper sash to thereby resiliently urge the upper and lower sashes apart.

2. A device of the character described comprising a supporting member formed of 10 an elongated wire loop, the wire loop at one end being bent to form a horizontal portion adapted to rest upon the upper face of a lower sash, a vertical portion adapted to

rest against the outer face of the sash and a portion extending upward and outward 15 and then inward from the lower end of said vertical portion and carrying at its upper end a roller, said last named portion of the supporting member being resilient to thereby urge the roller inward against the face 20 of the upper sash to thereby hold the sashes yieldingly urged apart.

In testimony whereof I hereunto affix my signature.

EDWARD J. PLAYFOOT.
